FIG. VI.

FIG. VII.

FIG. VIII.

FIG. IX.

Inventor:

VICTOR MAUCK,

*By Victor E. Page,
Attorney.*

UNITED STATES PATENT OFFICE.

VICTOR MAUCK, OF NORRISTOWN, PENNSYLVANIA, ASSIGNOR TO JOHN WOOD MANUFACTURING COMPANY, OF CONSHOHOCKEN, PENNSYLVANIA, A CORPORATION OF PENNSYLVANIA.

PROCESS OF MAKING CANS.

Original application filed April 14, 1921, Serial No. 461,274. Divided and this application filed March 10, 1922. Serial No. 542,742.

My invention is especially designed and adapted for the formation of cans used in the transportation and storage of ice-cream. Such cans are used by wholesale manufacturers to deliver ice-cream, water ice, frozen custards etc., to retail dealers, and are used by the latter as containers for such products while they are being dispensed; the emptied cans being thereafter returned to the wholesalers to be refilled and again distributed. Therefore, such cans must be extremely durable to withstand the repeated rough handling and consequent extreme stresses and wear to which they are inevitably subjected by such hard usage.

Moreover, as cans charged with such perishable commodities must be retained in ice water or other refrigerant liquid, their bodies must be permanently liquid tight, and, in order to prevent contamination of their contents, they must be adapted to be substantially hermetically sealed by their removable closures and yet capable of being instantly opened and closed to facilitate dispensing of their contents. Furthermore, as it is customary to dispense ice-cream and similar products by means of substantially hemispherical measuring scoops; such cans must be so designed that substantially all of their contents may be readily removed by such scoops.

Therefore, the object and effect of my invention is to provide cans having the characteristics above contemplated. However, it is to be understood that I do not desire to limit my invention to such specific use.

This is a division of my application Serial No. 461,274 filed April 14, 1921, and the can forming mechanism herein contemplated is claimed in that case.

In the drawings; Fig. I is a perspective view of a can constructed by the process herein claimed, and provided with a removable lid closure.

Fig. II is a vertical sectional view of the can and closure shown in Fig. I, showing the substantially sealed relation thereof.

Fig. III is a perspective view of a sheet metal cylinder which is the blank from which the body of the can shown in Figs. I and II is formed.

Fig. IV is a perspective view of a cylindrical ring of sheet metal which is the blank

adapted to form the flange to support and seal said lid closure on the can body.

Fig. V is an elevation of the ring shown in Fig. IV, but partly expanded toward its final flanged form.

Fig. VI is an elevation of the partly formed can body with the completed flanged ring fitted upon the top thereof; the bottom of said body being flared to receive the bottom plate.

Fig. VII is a diametrical sectional view of a bottom plate adapted to be fitted in the flared end of the can body shown in Fig. VI.

Fig. VIII is a diagrammatic axial sectional view of said can body, flange ring and bottom plate; showing said bottom plate supported upon its spinning mandrel and the opposite end of said body supported upon its expanding and supporting mandrel.

Fig. IX is a fragmentary axial sectional view of said can body and bottom plate, similar to Fig. VIII, but showing the rim of the bottom plate partially spun over the bottom of the can.

Fig. X is a fragmentary sectional view of substantially full size, showing the joint between the can body and the bottom plate as it exists in a finished can.

Referring to Figs. I to X inclusive, which shows a convenient form of ice-cream can constructed in accordance with my invention; the can body 1 having the removable lid closure 2, conveniently provided with the rigid handle 3, is formed of primarily flat sheet metal. A rectangular piece of such metal, conveniently low carbon steel, is first bent to the cylindrical blank form 5 indicated in Fig. III and then united at its abutting edges 6, conveniently by an electric welding operation, to form a blank from which the body of a can such as shown in Figs. I and II is formed. A cylindrical ring 8 of sheet metal, shown in Fig. IV, is similarly bent and united at its abutting edges 9 to constitute a blank from which may be formed the flange ring 10, as a fixture upon said can body 1, as indicated in Fig. II, to support said lid closure 2 and substantially hermetically seal the joint between the bottom edge of said closure and the can, when in the position shown in Fig. II. Said flange ring blank is expanded, by

a pressing operation, from the cylindrical form shown in Fig. IV to the form shown in Fig. V; then pushed upon said cylindrical can blank 5 until its upper edge is flush with the top of the latter. Thereupon, the expanded skirt 11 of said ring blank 10 is pressed inwardly, against said blank 5 until it is curled to form the toric bead 12 indicated in Figs. I, II, VI and VIII. That 10 pressing operation constricts said ring bead 12 upon said can blank 5. However, I subsequently expand said can blank 5 within said flange ring 10, slightly stretching the metal of both of said parts, to insure that 15 they shall thereafter remain in intimate contact. Such expansion is conveniently effected by thrusting the mandrel 13 into said blank 5, as indicated in Fig. VIII.

However, during the aforesaid operation 20 of forming said bead 12 upon said can body 5; I find it convenient to expand the bottom edge of said blank 5 as indicated at 14 in Fig. VI, so that said blank will readily fit over the bottom plate 15 as shown in Fig. 25 VIII. Moreover, as the commercial sheet metal, of which said blank 5 is formed, is primarily in an annealed soft ductile state, such working of the bottom edge of said blank 5, which as hereinafter described, is 30 ultimately rolled back to cylindrical form, imparts to it a desired degree of stiffness to resist deformation of the bottom edge of the can by the subsequent usage to which it is subjected.

35 Said bottom plate 15 is also formed from primarily flat sheet metal, by pressing operations which first cut a circular disk of such metal and then distort it to the cylindrical form shown in Fig. VII. It is to be particularly noted that the circumferential edge 40 16 of the cylindrical portion 17 of said bottom plate 15, which is presented upwardly in the can against the inner face of the cylindrical wall of the latter, as shown in Figs. 45 VIII, IX and X, is substantially sharp so that there is no crevice formed at the junction of said blanks 5 and 15. It may be observed that, because said edge 16 is thus sharp and as large in diameter as may be 50 to ultimately tightly fit the inner circumference of the blank 5, and because it is impossible to make said blank 5 precisely circular; it would be extremely difficult, if not impossible, to fit the substantially sharp 55 edge 16 of the cylindrical portion 17 within said blank 5, if the latter were not previously outwardly flared, as above described. The flared lower edge 14 of said blank 5 is then constricted upon said cylindrical portion 60 17 of the bottom plate, as shown in Fig. VIII. Thereafter, the primarily plane annular flange 18 of said bottom plate 15 is bent over the adjacent edge of said can body blank 5, first, as indicated in full lines 65 in Fig. IX, and, finally, to the form shown

in Fig. X wherein said annular flange 18 of the bottom plate 15 is cylindrical and in contact with the outer surface of the cylindrical wall of the can body 1; the cylindrical portion 17 of said bottom plate being likewise in 70 contact with the inner surface of said cylindrical wall of the can body 1. As herein-after described, I find it convenient to thus distort said bottom plate flange 18 while spinning it upon the mandrel 19 held under 75 pressure in opposition to said mandrel 13; and by the spinning roller 20, which is movable both parallel with, and transversely to, the axis of said flange, and while said mandrels 13 and 19 are rotated in coaxial relation.

Finally, said can body 1 is coated, all over, with a film of some material capable of resisting the corrosive effect of water upon the ferric metal parts of the can above described. For instance, I find it convenient to coat the can with such a film 20 of block tin, as indicated in Fig. X; so that the entire surfaces of said can 1 and its closure 2 are smoothly continuous and, consequently, 90 may be readily cleaned by washing them.

Although there are various novel features of procedure in the construction of the can above described; the claims in this case are limited to the process whereby the top of the can blank 5 and its ring 10 are expanded, and the bottom of the can constricted upon its bottom plate 15 and the flange 18 of the latter constricted upon said can body as above described. It is to be particularly 100 noted that it is an object and effect of the latter operation to minimize the radial projection of the bottom joint of the can, because, to preserve their lacteal contents such cans are embedded in broken ice, in tubs, during transportation and storage and the ice melts into such close conformity with the exterior of the cans that upon any attempt to lift the cans from the ice, the latter is inadvertently lifted and spilled out of 105 said tubs by any projecting portion of the cans thus embedded. Therefore, the can body blank 5, which is outwardly flared at its bottom edge 14 by the operation illustrated in Fig. IV, is finally left in its previously straight cylindrical form as shown 110 in Figs. III and X to minimize the radial projection of the bottom joint; as distinguished from ordinary can joints wherein the can body itself is outwardly flanged at 115 its bottom junction.

I do not desire to limit myself to the specific details of construction, or arrangement, or procedure herein set forth, as it is obvious that various modifications may be made therein without departing from the essential features of my invention, as defined in the appended claims.

I claim:

1. The process of can forming which 120

- consists in forming a cylindrical can body from a primarily plane sheet of metal by bending said sheet and joining the edges thereof; said edges being in a joint of substantially the same thickness as said sheet; fitting a flange ring over one end of said can body; simultaneously forming a bead on said ring and expanding the opposite end of said can body, to flared form; fitting in the flared end of the said can body a cylindrical portion of a bottom plate having a primarily plane flange at right angles to the axis of said body; simultaneously expanding said body within said ring and over said bottom plate by thrusting said body axially with respect to said bottom plate, between opposed mandrels in coaxial relation; rotating said body ring and bottom plate together, by said mandrels; and spinning said bottom plate flange over said body, to substantially concentric cylindrical relation with said body, and thus returning said flared end to its previous cylindrical form, during the rotation of said parts.
- 15 3. The process of can forming which consists in forming a hollow cylindrical can body, of uniform inside and outside diameter and having a cylindrical edge at each end thereof; fitting in one end of said can body a cylindrical portion of a bottom plate having a primarily plane flange at right angles to the axis of said body; rotating said body and bottom plate together while deforming said flange from its primarily plane form to cylindrical form, by pressure of a spinning roller thrust transversely to the axis of rotation of said body and bottom plate; until said flange is spun to cylindrical form, over said body, in hermetically tight relation therewith, during the rotation of said parts.
- 20 2. The process of can forming which consists in forming a cylindrical can body, of uniform inside and outside diameter and having a cylindrical edge at each end thereof; expanding one end of said can body, to flared form; thereafter fitting in the flared end of said can body, a substantially sharp edged cylindrical portion of a bottom plate having a primarily plane flange at right angles to the axis of said body; thrusting said body axially with respect to said bottom plate, between opposed mandrels in coaxial relation; rotating said body and bottom plate together, by said mandrels; and spinning said bottom plate flange over said body, to substantially concentric cylindrical relation with said body, and thus returning said flared end to its previous cylindrical form, during the rotation of said parts.
- 25 4. The process of can forming which consists in forming a hollow cylindrical can body, of uniform inside and outside diameter and having a cylindrical edge at each end thereof; fitting in one end of said can body a cylindrical portion of a bottom plate having a primarily plane flange at right angles to the axis of said body; rotating said body and bottom plate together while deforming said flange from its primarily plane form to cylindrical form, by pressure of a spinning roller thrust transversely to the axis of rotation of said body and bottom plate; until said flange is spun to cylindrical form, over said body, in hermetically tight relation therewith, during the rotation of said parts.
- 30 5. The process of can forming which consists in forming a cylindrical can body, of uniform inside and outside diameter and having a cylindrical edge at each end thereof; expanding one end of said can body, to flared form; thereafter fitting in the flared end of said can body, a substantially sharp edged cylindrical portion of a bottom plate having a primarily plane flange at right angles to the axis of said body; thrusting said body axially with respect to said bottom plate, between opposed mandrels in coaxial relation; rotating said body and bottom plate together, by said mandrels; and spinning said bottom plate flange over said body, to substantially concentric cylindrical relation with said body, and thus returning said flared end to its previous cylindrical form, during the rotation of said parts.

In testimony whereof, I have hereunto signed my name at Conshohocken, Pennsylvania, this 27th day of February, 1922.

VICTOR MAUCK.
